SHEET METAL DISPLAY CAN OR BOX.

APPLICATION FILED JAN. 14, 1904.

NO MODEL.

Fig. 1

Fig 2 f as 3 p q4 a1

This technical drawing illustrates a double frame structure, likely a window or door frame, with various internal components and labels:

- Outer Frame:** The outer frame is defined by labels **A'** at the top and bottom corners and **B** on the left and right vertical sides.
- Inner Frame:** The inner frame is defined by labels **A'** at the top and bottom corners and **B** on the left and right vertical sides.
- Internal Components:**
  - G**: A central rectangular component.
  - G'**: A smaller rectangular component located within **G**.
  - H**: A curved component positioned above **G**.
  - H'**: A curved component positioned above **G'**.
  - I**: A small rectangular component located below **G**.
  - J**: A curved component positioned below **G'**.
  - J'**: A curved component positioned below **I**.
  - J''**: A curved component positioned below **J**.
  - K**: A small rectangular component located below **J**.
  - L**: A small rectangular component located below **K**.
  - M**: A small rectangular component located below **L**.
  - N**: A small rectangular component located below **M**.
  - O**: A small rectangular component located below **N**.
  - P**: A small rectangular component located below **O**.
  - Q**: A small rectangular component located below **P**.
  - R**: A small rectangular component located below **Q**.
  - S**: A small rectangular component located below **R**.
  - T**: A small rectangular component located below **S**.
  - U**: A small rectangular component located below **T**.
  - V**: A small rectangular component located below **U**.
  - W**: A small rectangular component located below **V**.
  - X**: A small rectangular component located below **W**.
  - Y**: A small rectangular component located below **X**.
  - Z**: A small rectangular component located below **Y**.
- Labels:** The drawing features numerous labels including **A'**, **B**, **C**, **D**, **E**, **E'**, **F**, **G**, **G'**, **H**, **H'**, **I**, **J**, **J'**, **J''**, **K**, **L**, **M**, **N**, **O**, **P**, **Q**, **R**, **S**, **T**, **U**, **V**, **W**, **X**, **Y**, **Z**, **a**, **a'**, **b**, **b'**, **b''**, **b'''**, **b⁴**, **b⁵**, **b⁶**, **b⁷**, **b⁸**, **b⁹**, **b¹⁰**, **c**, **c'**, **d**, **e**, **f**, **g**, **g'**, **g²**, **g³**, **h**, **h'**, **i**, **j**, **j'**, **j''**, **k**, **l**, **m**, **n**, **o**, **p**, **q**, **r**, **s**, **t**, **u**, **v**, **w**, **x**, **y**, and **z**.

UNITED STATES PATENT OFFICE.

BERNARD H. LARKIN, OF AUSTIN, ILLINOIS, ASSIGNOR TO AMERICAN CAN COMPANY, OF JERSEY CITY, NEW JERSEY, A CORPORATION OF NEW JERSEY.

SHEET-METAL DISPLAY CAN OR BOX.

SPECIFICATION forming part of Letters Patent No. 764,297, dated July 5, 1904.

Application filed January 14, 1904. Serial No. 188,973. (No model.)

To all whom it may concern:

Be it known that I, BERNARD H. LARKIN, a citizen of the United States, residing in Austin, in the county of Cook and State of Illinois, have invented a new and useful Improvement in Sheet-Metal Display Cans or Boxes, of which the following is a specification.

My invention relates to improvements in display cans or boxes of sheet metal designed to contain crackers, bakery goods, and other like articles.

The object of my invention is to provide a sheet-metal display can or box suitable for containing crackers, bakery articles, and other goods and having at its front two openings, one closed by a removable sign-plate and the other by a removable glass plate to display to view the contents of the can or box, in which the removable plates will be securely held in place, so that there will be no danger of either falling out or becoming displaced in shipment or handling of the can or box, in which the glass or display plate can only be removed by first removing the sign-plate, and which will at the same time be of a neat, strong, simple, efficient, and durable construction, capable of being cheaply manufactured.

My invention consists in the means I employ to practically accomplish this object or result—that is to say, it consists in a sheet-metal display can or box having a body, bottom, and hinged cover and in which the sheet-metal front of the body is provided with two openings and with integral guides surrounding the upper opening for holding the upper removable plate in place and with an integral bearing to support a pivotal or hinged catch, which hinged catch has a lower arm or lip that engages the upper edge of the lower removable plate to hold it in place, and also with an upper arm that engages the upper removable plate to hold the hinged catch in operative position, so that the lower removable plate cannot be removed without first removing the upper removable plate.

My invention further consists in the novel construction of parts and devices and in the

novel combinations of parts and devices herein shown and described.

In the accompanying drawings, forming a part of this specification, Figure 1 is a perspective view of a sheet-metal display box or can embodying my invention. Fig. 2 is an enlarged central vertical section on line 2 2 of Fig. 1. Fig. 3 is a vertical section on line 3 3 of Fig. 2. Fig. 4 is a horizontal section on line 4 4 of Fig. 2, and Fig. 5 is a vertical section on line 5 5 of Fig. 4.

In the drawings, A A A represent the three vertical sides, which, in connection with the front B, forms the body of the can or box.

C is its bottom, and D the hinged cover.

Each of the three sheet-metal side plates A, which are preferably of tin-plate, and the sheet-metal front B, which is preferably of brass, are secured at their lower edges to the bottom C by external folded seams or lock-seams a' , formed by interfolded flanges $a c$ and $b c$ at the meeting edges of the sides A and front B with the bottom C. These external interfolded or lock seams not only serve to unite the body of the can or box to its bottom, but also to materially strengthen the can or box as a whole, which is ordinarily of considerable size—one customary size, for example, being twelve inches high by about ten inches square in horizontal section. At the upright corners of the body, the sheet-metal side plates A A and front B are united together by internal folded seams or lock-seams a' , formed by interfolded flanges $a^2 a^2$ and $a^2 b'$ on the upright meeting edges of the side plates A and front plate B, thus not only uniting the side plates and front of the body of the can or box, but also materially stiffening and strengthening the can or box. To strengthen and stiffen the upper end of the body of the can or box and form a flat seat for the hinged cover to fit and shut down upon, the vertical sides A of the body are provided with horizontal or right-angle flanges a^3 , preferably about one-half inch in width, and with angle-flanges a^4 , preferably about three-fourths of an inch in width, the lower edges of which

- meet the vertical sides A of the can or box, thus forming hollow triangular stiffening bars or braces A' at the upper end of the body of the can or box, at three sides thereof, and at 5 its remaining or front side a similar hollow strengthening and stiffening bar or brace A², composed of sheet metal, and having a corresponding right-angle or horizontal flange a³ and angle-flange a⁴, is provided. At the corners of the body the meeting horizontal flanges a³ and meeting angle-flanges a⁴ of the hollow strengthening bars or braces A' A² overlap each other and are securely soldered together, thus forming a continuous hollow strengthening bar or brace all around the upper end 15 of the body, thus giving the body a very stiff, strong, and rigid construction.
- The front B of the body, which is preferably of sheet-brass to give a neater and more 20 ornamental appearance to the display can or box, is provided with two openings B' and B², one above the other, each surrounded by an inturned angle-flange b². The lower or display opening B' is closed by a removable glass or 25 transparent plate E, and the upper or sign opening B² is closed by a removable sign-plate F. The upper or sign plate F is inserted through a slot or passage-way f between the front hollow brace or bar A² and the sheet- 30 metal front B of the box-body. This plate F is held in position by fixed metal guides b³ b³, one for each end of the plate F, formed integrally on the sheet-metal front B surrounding the opening B² therein, and by a lower or 35 bottom guide b⁴, likewise formed integrally on the sheet-metal front B of the box. The guides b³ consist of suitable folds b⁵ in the integral flanges b⁶ of the front B at the two ends of the upper opening B² therein, and the lower guide 40 b⁴ likewise consists in a suitable fold b⁷, formed in the integral lip or flange b⁸ on the box-front B at the lower margin of the upper opening B² therein. The flange b⁸ on the box-front B at the lower margin of the upper 45 opening B² therein has an upward extension b⁹, furnished with a roll or socket b¹⁰ to form a bearing for the pivot or hinge pin g of the hinged catch G, which serves to hold the lower glass or display plate E in place. This 50 hinged catch G is preferably made of sheet metal and is provided with a lip or lower edge g', which engages the upper edge of the glass plate E to hold the same in place. It is also provided with an upper integral arm g², 55 which is adapted to engage and press against the sign-plate F. The sign-plate thus holds the hinged catch in its operative position and prevents the hinged catch from turning or swinging so as to close the lower or glass plate without first removing the upper or sign 60 plate. The hinged catch G has curved lips or coils g³ to secure the same to the pivot pin or wire g. The hinged catch G is also provided with an offset or shoulder g⁴ for the upper edge of the lower or glass plate E to abut 65

against. The glass or display plate E rests at its lower edge on the bottom of the box and is held in position at its lower edge by a fixed sheet-metal guide E', the edge e of which is interfolded with the flanges b² c of the front 70 and bottom, thus securing this guide firmly in place without the necessity of soldering. This fixed guide E' has an upturned lip or flange E² to engage the lower edge of the glass plate E. 75

In operation the lower or glass plate E is first put in place, the hinged catch G is then turned into operative position to hold the glass plate in place, and then the sign-plate F is slipped into place through the slot or passage-way f, thus causing it to engage and press against the upper arm of the hinged catch G, and thereby holding it in operative position. To remove the plates E and F, the sign-plate F must be first removed, and then the hinged catch G can be turned and the lower or glass plate removed. As in my invention the fixed guides for one of said removable plates is formed integrally in one piece with the sheet-metal front of the box 90 by suitable folds at the edges of the front plate surrounding the opening therein and as the movable catch or guide for the other removable plate is mounted on an integral flange or fold of the sheet-metal front itself, the construction of the display-box is greatly simplified and its cost of manufacture materially reduced, while at the same time the box itself is materially improved. 95

I claim—

1. A display can or box having a front furnished with two openings, removable plates for closing said openings, said front having integral guides for one of said plates at the edges of one of said openings, and a movable catch for one of said plates held in operative position by its engagement with the other of said plates, substantially as specified. 100

2. A display can or box having a front furnished with two openings, removable plates for closing said openings, said front having integral guides for one of said plates at the edges of one of said openings, and a movable catch for one of said plates held in operative position by its engagement with the other of said plates, said movable catch being mounted on an integral flange formed on said front, substantially as specified. 110

3. A display can or box having a sheet-metal front furnished with two openings therein and with integral guides for one of said plates, and a hinged catch having a lip or arm engaging one of said plates to hold it in place and provided with another arm engaging the other plate to cause said catch to be held in operative position, substantially as specified. 115

4. A display can or box having a sheet-metal front furnished with two openings therein and with integral guides for one of said plates, and a hinged catch having a lip or arm 120

130

engaging one of said plates to hold it in place and provided with another arm engaging the other plate to cause said catch to be held in operative position, said sheet-metal front being also provided with an integral bearing or support for said hinged catch, substantially as specified.

5. A display can or box having a sheet-metal front furnished with two openings therein, and with an integral bearing for a hinged catch, two removable plates closing said openings and a hinged catch mounted on said front for holding one of said plates in place and provided with an arm engaging the other plate to cause said catch to be held in operative position thereby, substantially as specified.

15. A display can or box having a front furnished with two openings, removable plates

for closing said openings, said front having fixed integral guides formed by integral folds 20 therein for one of said plates and a movable catch for the other plate, substantially as specified.

7. A display can or box having a front furnished with two openings, removable plates 25 for closing said openings, said front having fixed guides for one of said plates, and a movable catch for the other of said plates, said front having an integral flange upon which said movable catch is mounted, substantially 30 as specified.
